United States Patent Office

Des. 195,589
Patented July 2, 1963

195,589

TOOL FOR HANDLING TILE OR THE LIKE

Joseph Charniga, Jr., R.D. Box 296, near Poland, Ohio

Filed Feb. 26, 1962, Ser. No. 68,970

Term of patent 14 years

(Cl. D54—13)

FIG. 1

FIG. 2

FIG. 3

FIGURE 1 is a perspective view of a tool for handling tile or the like, showing my new design;

I claim:

The ornamental design for a tool for handling tile or the like as shown.
